Primary Examiner — Holly E Thurman*Assistant Examiner* — Ieisha N Price(74) *Attorney, Agent, or Firm* — Dennis L. Thomte;
Thomte Patent Law Office LLC(57) **CLAIM**

The ornamental design for an insulation retainer clip, as shown and described.

DESCRIPTION

FIG. 1 is a top, front, right side perspective view of the insulation retainer clip;

FIG. 2 is a right side view of the insulation retainer clip;

FIG. 3 is a top plan view of the insulation retainer clip;

FIG. 4 is a front elevation view of the insulation retainer clip;

FIG. 5 is a bottom plan view of the insulation retainer clip;

FIG. 6 is a rear elevation view of the insulation retainer clip; and,

FIG. 7 is a left side view of the insulation retainer clip.
